UNITED STATES PATENT OFFICE.

ROBERT S. NEWALL, OF GATESHEAD, COUNTY OF DURHAM, ENGLAND.

MACHINE FOR MAKING WIRE ROPE.

SPECIFICATION forming part of Letters Patent No. 366,422, dated July 12, 1887.

Application filed February 10, 1886. Serial No. 191,452. (No model.) Patented in England April 13, 1885, No. 4,559.

To all whom it may concern:

Be it known that I, ROBERT STIRLING NEWALL, of the borough of Gateshead, in the county of Durham, England, have invented certain new and useful Improvements in Machines for Making Wire Ropes, of which the following is a specification, reference being had to the drawings forming part thereof, in which—

Figure 1 is a side view of the machine. Fig. 2 is an end view of the front bearing-wheels and frame. Fig. 3 is a plan of the drawing-gear and the forward end of the twisting-machine. Fig. 4 is a plan view of a piece of the completed rope. Fig. 5 represents one of the strands; and Fig. 6 shows a detail sectional view of the forward end of one of the bobbin-frames and the guide *v* and nozzle *w*, the forward end of the main shaft and the laying-plate being also shown, and a detail view in cross-section of the forward end 20 of the bottom frame.

The invention will be first described, and then pointed out in the claims.

a is the main shaft of the machine, which has a hole through it for the core of the rope 25 to pass through. It has fixed on it at right angles the driving-wheel *a'*, worked by motive power, the back arms, *b*, and the front arms, *c*, each having six or other required number of bearings for supporting the strand-frames *A*, 30 which rotate in the bearings in the arms *b* and *c*. Each frame is constructed to hold the number of bobbins *A'*, each containing a separate wire, *A*², necessary to make a strand, *A*³, and one bobbin containing the core *A*⁴, which may 35 be made of wire or hemp or other material.

In the top part of Fig. 1 the strand-frame *A* is in side elevation, showing the three central bobbins, which are shown in plan at the bottom of the said figure. At the backs of the main 40 arms *b* there are wheels for causing the strand-frames to rotate backwardly in their bearings once for each revolution they make round the axis of shaft *a*. These consist of a bevel-wheel, *b'*, fixed on the end of each bobbin-frame, and 45 a wheel, *b*², of the same size, fixed to the supporting-pillar *a'*, through which the main shaft *a* works. Two pinions, *b*³, of equal size, are fixed on each shaft *b*⁴, and communicate motion to the frame-wheels by being carried 50 round the fixed wheel, and thus the torsion of

the wires and the strands is prevented while they are being laid into a rope. The front arms, *c*, form a wheel, *C*, which rotates on two other wheels, *d* and *e*, supported in a frame, *C'*, forming the front bearing of the machine, as 55 shown in Fig. 2. These three wheels are V-grooved on the surface, so as to have more adhesion between *C* and *d*, and at the same time to prevent the machine being drawn toward the drawing-gear. There is fixed on the outer 60 end of the axle of the wheel *d*, Fig. 1, a toothed wheel, *f*, which works into another wheel, *g*, which is supported by a swinging link, *g'*, hanging from the axle *d'*, and working concentrically with the wheel *f*, so as to be always 65 in gear with it.

h is one of a set of change-wheels of different diameters proportional to a gear-wheel, *i*, by means of which "the draw" is regulated. The change-wheels *h* slip on a tube 70 or sleeve, one end of which is fixed in wheel *g*, so that wheels *g* and *h* rotate together on a pin projecting from the swing-link *g'*, and as wheel *h* gears into *i* the required speed is given to the wheel *i*, which is fixed on the 75 shaft *i'*, which carries at the other end the bevel-wheel *j*, working into another bevel-wheel, *k*, on the axle of which is fixed the toothed wheel *l*, which works into the wheel *m*, fixed on the side of the drawing-drum *m'*, 80 as shown in the drawings. There are two bevel-wheels *k*, one on each side of *n*, so that by pushing one into gear with *n* and pushing the other out either right or left hand ropes are made. These wheels *k* have set-screws 85 passed through their hubs for holding them when adjusted on their shaft.

On the bed-plate which supports the front bearings there are also fixed four upright pillars, *C'*, which carry the four drawing-rollers 90 *D* and drum *m'* and wheels *n p r u o q s t*. On the two lower shafts are fixed two toothed wheels, *n p*, which gear into wheel *m*, and on the same lower shafts, and under the wheels *r u*, are fixed two other wheels, *o q*, which 95 gear into wheels *r u*, and these into wheels *s t*, which are fixed on the upper shafts. On the four shafts which carry the wheels *r s t u* there are grooved drawing-rollers *D*, which are capable of sliding along the shafts on keys let into 100

the shafts, so as to couple the shafts and rollers together, and so as to bring the properly sized grooves in a line with the axis of the main shaft *a*. These rollers grip the rope, 5 and by the rotation of the machine and the action of the wheels described they draw off from the bobbins a certain length of wire for each rotation of the machine, and so form a rope composed of strands of wires *A*³, which 10 strands are not subjected to torsion, as is usual in rope-making; but the rope may be drawn by taking several turns of it round the drum without using the rollers, or it may be drawn by the combined action of rollers and drum, 15 for they both go at the same surface-speed.

The wires from the bobbins pass through the front journal of the strand-frame, where they are symmetrically arranged round a core, and they also separately pass through the 20 guides *v* and nozzles *w*, which project from each frame, and which rotate in the plate *x*. The bobbin-frames are tubular at their forward or inner ends, and the cores from the several bobbin-frames pass entirely through 25 these tubular ends, while the several wires enter said tubular portions and pass outward therefrom through six apertures, 1.

The guides *v* are formed of plates secured to or formed on the said tubular portions and 30 having in the present instance six apertures, through which the wires pass from the apertures 1. The nozzles *w* are also provided with six apertures to receive the wires from the guides *v* and are screw-threaded to engage 35 screw-threads on the extreme ends of the tubular portions of the said bobbin-frames, as clearly shown in Fig. 6, and these nozzles rest in bearings in the plate *x*, so that they form the journals of the inner ends of the tubular 40 portions of the bobbin-frames. The wires from each strand-frame being thus kept separate and without being subjected to torsion, are laid in separate strands or sets round a core into a rope without being laid or twisted together in the usual way of making wire rope. 45

I have illustrated the description of my invention by drawings of a machine in which the main shaft is horizontal, which I prefer to having the main shaft perpendicular; but my 50 improvement is easily applied to a perpendicular machine so long as the strand-frames make one rotation on their axes while the machine rotates once.

The drawings show a machine for making 55 ropes of six strands, each strand having six wires and a core; but machines may be made having any other number of wires, cores, and strands.

Having thus described my invention, what 60 I claim as new is—

1. The combination, with the main shaft having circularly-arranged bearings at its opposite ends, and the strand-frames journaled at their opposite ends in said bearings and 65 each having a series of bobbins, of gearing, substantially as described, on the bobbin-

frames and their rear bearings, to revolve said frames backwardly once for every revolution of the main shaft, substantially as set forth.

2. The combination, with the main shaft *a*, 70 having the driving-wheel *a*², the arms *b c*, fixed to the driving-shaft, and the bobbin or strand-frames *A*, each having a series of bobbins, of the bevel-wheels *b'* on the rear ends of the frames, the shafts *b*⁴, journaled on the arms *b* 75 and parallel therewith, the bevel-pinions *b*³, of equal size, on the opposite ends of said shafts, the fixed bevel-wheel *b*², concentric with the shaft *a* and of the same size as the wheels *b'*, whereby when the main shaft and its arms 80 are rotated once the frames *A* will also be revolved backwardly once and twisting of the individual wires and strands prevented, substantially as set forth.

3. The combination, with the main shaft 85 having arms at its rear end and a fixed friction-wheel at its forward end provided with bearings, the bobbin-frames journaled in said bearings and arms, and an operating mechanism, of friction-wheels supporting the fixed 90 friction-wheel and rotated thereby, gearing connected with and operated by one of said supporting friction-wheels, and the drawing mechanism operated from said gearing, substantially as set forth. 95

4. The combination, with the main shaft having arms at its rear end and a fixed friction-wheel at its forward end provided with bearings and a grooved periphery, the bobbin-frames journaled in said arms and wheel, 100 and an operating mechanism, of the grooved friction-wheels engaging and operated by the fixed friction-wheel, a drawing mechanism, and intermediate gearing connecting said drawing mechanism with one of said supporting 105 friction-wheels, substantially as set forth.

5. The combination, with the main shaft having arms at its rear end, and a fixed wheel at its forward end provided with bearings, bobbin-frames journaled in said arms and 110 wheel, and an operating mechanism, of wheels engaging the said fixed wheel and operated thereby, the drawing mechanism, and intermediate gearing connecting one of said wheels operated by the fixed wheel with the drawing 115 mechanism, and having a change-wheel, whereby the draw may be regulated, substantially as set forth.

6. The combination, with the main shaft *a*, 120 its arms *b*, wheel *C*, the frames *A*, and gearing, substantially as described, for operating the said frames, of the friction-wheels *d e*, on which the wheel *C* rests, a gear-wheel, *f*, on the axle *d'* of wheel *d*, a swinging link, *g'*, also mounted on said axle *d'*, and having the gear-wheel *g* meshing with gear-wheel *f*, the gear-wheel *h*, connected with the gear *g* and operated thereby, the shaft *i'*, having a gear-wheel, *i*, engaging the wheel *h*, and the gear-wheel *j* on the opposite end of said shaft, and the 130 drawing mechanism operated from the gear-wheel *j*, substantially as set forth. 125

7. The combination, with the twisting-frame, the shaft i' , and mechanism for operating said shaft from the twisting-frame, of the drawing-rollers D D, their shafts, intermeshing gears $s r t u$ on said shafts, the gear-wheels $o q$ below and meshing with the gears $r u$, respectively, the gears $n p$ on the same shafts as the gears $o q$, the intermediate shaft, m^3 , the drum m' thereon, the gear-wheel m on the side

of the drum and meshing with the gears $n p$, o the gear-wheel l , meshing with the gear m , the bevel-gear k on the shaft of the gear l , and the bevel-gear j on shaft i' and meshing with the gear k , substantially as set forth.
